(57) **CLAIM**

The ornamental design for a bat exclusion device, as shown and described.

DESCRIPTION

FIG. 1 is a top front left side perspective view of a bat exclusion device showing my new design;

FIG. 2 is a top front right side perspective view of the bat exclusion device;

FIG. 3 is a left side view of the bat exclusion device;

FIG. 4 is a right side view of the bat exclusion device;

FIG. 5 is a front view of the bat exclusion device, a rear view being a mirror image thereof;

FIG. 6 is a top view of the bat exclusion device; and,

FIG. 7 is a bottom view of the bat exclusion device.
